WALTER CHIPPERFIELD, OF ROMFORD, ENGLAND, ASSIGNEE TO WILLIAM EDWARD GARFORTH, OF PONTEFRACT, ENGLAND.

KINEMATOGRAPH CAMERA AND PROJECTING APPARATUS

1,082,305.

Specification of Letters Patent. Patented Dec. 23, 1913.

Application filed April 22, 1913. Serial No. 762,870.

To all whom it may concern:

Be it known that I, WALTER CHIPPERFIELD, engineer, a subject of the King of Great Britain, residing at "Kinkora," 5 Woodlands avenue, Great Nelmes, Hornchurch, Romford, Essex, England, have invented certain new and useful Improvements in Kinematograph Cameras and Projecting Apparatus, and of which the following is a specification.

This invention relates to kinematograph cameras and projecting apparatus, in which a film passes over a wall of a stationary casing or frame of the operating mechanism 10 and between said wall and a yielding gate prior to being engaged by the feeding device, which latter consists of a pressure roller yieldingly supported by the said stationary frame, and a feed roller carried in 15 stationary bearings in the said stationary case or frame. The said case or frame carries mechanism by which said feed roller is driven, and between which said rollers the film passes.

The object of the present invention is to 20 provide means to prevent the possibility of the film leaving the desired path and becoming entangled with the mechanism.

The invention is illustrated in the accompanying drawings, in which,

Figure 1 is a sectional side elevation showing the feed rollers in their operative position. Fig. 2 is a front elevation of the gate detached from the camera mechanism, 35 and showing the pressure roller in position with relation thereto. Fig. 3 is a sectional plan of Fig. 1.

The apparatus comprises a frame or case A carrying in stationary bearings a feed 40 roller B driven in a well known manner by spur gearing from suitable mechanism, which also operates a revolving shutter, a pressure roller C being yieldingly supported from the said frame and adapted to operate 45 in conjunction with raised portions D on the feed roller B, to feed the film G between the wall F and a gate H and intermittently past an exposure aperture E in the front wall F.

It has been usual in such apparatus to 50 form the rollers B and C with continuous surfaces in the direction of their axes and to form the wall F of the casing with an aperture through which the raised peripheral portions D of the roller B project

from time to time as the roller is revolved. The raised portion or portions D of the roller B, (that is those segments which have a greater radius than the normal diameter of the roller) extend only in the direction of the axis of the roller, while the pressure roller C which had a continuous surface both in the direction of its axis and in the direction of its periphery was carried below the lower end of a gate, and with such an arrangement it has been found that the film has been liable to curl either around the feed or pressure roller, instead of keeping to the desired path when the film is first inserted in the feeding mechanism. To prevent such an occurrence both the rollers B and C are constructed in multiple, it may be in duplex form, by forming them with a central cut away portion B¹ and C¹ respectively thus leaving two projecting side portions of greater diameter than the central portion. The front wall F of the case is then formed with two independent apertures, a central dividing strip J being left, and through these apertures the raised peripheral portions of the roller B project, the said strip forming a continuous surface with the wall F.

K is the gate between which and the wall F the film G passes, and this gate is carried 85 by a frame L, having bearings in which the pressure roller C is supported, the said frame L being pivoted at M to the frame A. This gate is of such a length that it extends below the periphery of the pressure roller C 90 and is formed, in a similar manner to the walls F with two apertures through which the periphery of the enlarged portions of the roller C project to co-act with the raised peripheral portions D of the feed 95 roller B to feed the film, a strip N of the said gate lying in the recess C¹ between the enlarged portions of the pressure roller C, said strip forming a continuous surface with the gate, over which surface the film passes. It 100 will thus be seen that should the film have a tendency to curl around the feed roller B it will be prevented from so doing by the strip J in the wall F and in a like manner the film will be prevented from curling 105 around the pressure roller C by the strip N of the gate K. Obviously the feed and pressure rollers may each be divided into more than two acting portions, and if desired may be composed of separate rollers 110

fixed on to a shaft with distancing pieces between them.

What I claim as my invention and desire to secure by Letters Patent is:—

- 5 Apparatus of the type specified for taking kinematograph pictures and projecting the same; comprising in combination a feed roller consisting of a plurality of acting portions spatially arranged in the direction of its axis, said acting portions projecting into apertures in the front wall of the frame carrying the feed roller driving mechanism, a strip forming part of the front wall and in face alinement therewith dividing adjacent apertures, an enlargement on the periphery of each acting portion adapted to project through said apertures, a pressure roller yieldingly supported by said mecha-
- 10
- 15

nism frame and consisting of acting portions spatially arranged in the direction of its axis and of a number corresponding to said acting portions of said feed roller, and a gate having apertures through which the acting portions of said pressure roller pass to coact with said feed roller to feed the film, a strip forming part of said gate and in face alinement therewith dividing adjacent apertures in said gate and passing between adjacent acting portions of said pressure roller.

In witness whereof I have hereunto set my hand in the presence of two witnesses.

WALTER CHIPPERFIELD.
